150,310

DESIGN FOR A TEXTILE FABRIC OR SIMILAR ARTICLE

Robert E. Minger, Manhattan Beach, Calif., assignor to Mabs, Inc., Los Angeles, Calif., a corporation of California

Application March 15, 1947, Serial No. 137,623

Term of patent 3½ years

(Cl. D92—1)

To all whom it may concern:

Be it known that I, Robert E. Minger, a citizen of the United States, residing at Manhattan Beach, county of Los Angeles, and State of California, have invented a new, original, and ornamental Design for a Textile Fabric or Similar Article, of which the following is a specification, reference being had to the accompanying drawing, forming part thereof.

The figure is a plan view of a piece of textile fabric or similar article showing my new design. The figure is a complete design unit. Said unit repeats vertically and horizontally over the textile fabric.

I claim:

The ornamental design for a textile fabric or similar article, substantially as shown and described.

ROBERT E. MINGER.
